UNITED STATES PATENT OFFICE.

JAMES W. CHANNELL, OF SOUTH GATE, CALIFORNIA.

SPLICING MACHINE.

Application filed July 17, 1925. Serial No. 44,257.

My invention relates to a machine for splicing wires of a telephone or telegraph cable, or other like structures, and is an improvement on the machine described in my application No. 684,814, filed January 1st, 1924, patented January 3rd, 1928, No. 1,654,788; and the object thereof is to produce a machine that will twist two wires together or a plurality of pairs of wires, and place an insulating sleeve over the twisted portions in a simpler and more efficient manner than the machine described in my other application and will be described as used in splicing telephone cable wires.

In the drawings forming a part of this application, Fig. 1 is a top plan of my machine positioned on a cable being spliced, showing some of the wires spliced, wires in the machine ready for splicing, other wires ready for placement, and other wires broken away. Fig. 2 is an enlarged top plan of the machine, and fragments of the cable connecting device. Fig. 3 is an enlarged top plan of the machine just as the wire twisting is finished. Fig. 4 is a front end elevation of the machine. Fig. 5 is a side elevation of the twist cutter. Fig. 6 is a side elevation of the sleeve clutch. Fig. 7 is a side elevation of the gear box. Fig. 8 is a side elevation partly broken away of the trigger standard. Fig. 9 is a side elevation of the detent lever with connected and adjacent parts partly in elevation and partly in section. Fig. 10 is a top plan of the compensating link, partly in section. Figs. 11 and 12 are side elevations of a double twist cutter, showing two positions. Fig. 13 is a side elevation of the gears that drive the twisters shown in Figs. 11 and 12. Fig. 14 is a side elevation of a double twist cutter. Figs. 15 and 16 are side elevations of a twister hook, showing two positions. Fig. 17 is a side elevation of a cable clamp. Fig. 18 is an edge view of Fig. 14. Fig. 19 is an edge view of Fig. 16. Fig. 20 is a perspective view of a release clutch, partly broken away.

Referring to the drawings, 25 is the base plate on which is rigidly mounted grip bar 26. An operating lever 27 is pivotally connected to bar 26 and plate 25 by bolt 28. A spring 29 connected to plate 25 and lever 27 normally holds lever 27 in its open position engaging stop 30 on plate 25. A tubular jacket 31 protects spring 29. Before commencing to use the machine, the ends of cable 32 are positioned in the manhole, not shown, in which the splicing operation is carried on. The lead

armor 33 is removed from the ends of the cable the required distance. The machine is then secured to the cable. This is accomplished as follows: A connector bar 34, best shown in Fig. 1, has a slot 35 extending longitudinally therein. Bolt 36 is passed through a slot 37 in plate 25 and the nut, not shown, placed thereon. A second bolt 38 is passed through a slot 39 in the other side of plate 25 and also through slot 37. The arrangement of these slots and bolts is best shown in Fig. 4. These bolts and slots adjustably secure plate 25 and bar 34 together so that plate 25 can be moved to the right or left or forward or backward with reference to bar 34. Secured to the ends of bar 34 are L shaped adjusting arms 40 and 41. A clamping member composed of an attaching jaw 42 and a movable jaw 43 are adjustably secured to arm 40 as follows: Jaws 42 and 43 are connected by clamp screw 44. Jaw 42 has a U shaped shank 45 in the outer member of which is a slot 46. A guide pin 47 mounted in arm 40 passes through slot 46. The upper end of the outer member of shank 45 is turned at right angles outwardly and is pierced. An adjusting screw threaded bolt 48 is revolvably mounted in the out-turned end of shank 45, but is not longitudinally movable therein. Bolt 48 passes through the base of arm 40 in threaded engagement therewith. By means of jaws 42 and 43 and screw 44 and connected parts, one end of the cable is secured to one end of bar 34. The other end of the cable is secured to the other end of bar 34 by like parts to those described and are for that reason not further described or illustrated. As shown, the corresponding parts are numbered with like numbers. By the revolution of bolt 48, plate 25 and connected parts are raised and lowered with respect to the cable; insulating sleeves 49 are placed on the wires at one end of the cable, shown as at the right in Fig. 1. In this figure only a part of the wires are shown with sleeves, but all the wires have sleeves when the splice is finished. These sleeves are positioned on the wires by the hand of an operator a few at a time as the splicing operation progresses. After a sleeve is positioned on a wire 50, the operator takes such wire and brings the same through a holding and ejecting device mounted on the right side of slide 51. This holding and ejecting device is composed of the following parts: A trigger standard 52 is rigidly secured upon the base plate 53 of slide 51. Standard

110

52 has a vertical slit 54 therein, in which slit is mounted a trigger 55 having a bill 56 and a lip 57. Standard 52 has a horizontal slit 58 across which bill 56 and lip 57 extend when 5 in the position shown in Fig. 8. A spring 59^a secured upon the top of the standard 52 yieldingly holds trigger 55 in the position shown in Fig. 8. Wire 50 is brought by the operator against lip 57. The trigger yields 10 to permit the wire to pass under the lip and it is then held between the lip and bill as shown in Fig. 8, in slit 58. He then brings the wire around skinning blade 59 and through guide 60. The operator takes the 15 companion wire 61 from the other end of the cable and brings it around skinning blade 62 and brings it through guide 60. When bringing the wires from the skinning blades to the shears the wires are turned sharply 20 around blades 59 and 62 (shown best in Fig. 9) and the paper insulation breaks at these blades and he strips off the paper insulation from the wires between the blades and the ends of the wires. At this time the sleeve 25 on wire 50 lies between standard 52 and guide lug 63 mounted on slide 51. Lever 27 has connected thereto a compensating link composed of a body member 64 (see Fig. 10) which is secured to 27 by screw 65. Member 64 has a bore therein in which is mounted the 30 end of connector pin 66, the outer end of which is reduced in size and has surrounding such reduced portion coiled spring 67 whereby a yielding motion is had between pin 66 and member 64. Pin 66 is connected to rack bar 68, which has rack teeth 69 on the top that engage a pinion 70, best shown in Fig. 13. Pinion 70 is rigidly mounted on shaft 71, on which is mounted a gear 72. Gear 72 meshes 40 with pinions 73 and 74 when the machine is designed to splice two pairs of wires at one operation. If only a single pair of wires is to be spliced, pinion 74 and connected parts would be omitted. Pinion 73 is mounted on shaft 75 and pinion 74 is mounted on shaft 76. Shaft 75 has rigidly mounted thereon a twister hook composed of a body 77 from which projects an arm 78. There is a notch 79 at the junction of the arm and body and when 45 shaft 75 is revolved the arm catches the wires and brings them into and holds them in notch 79. Shaft 76 has rigidly mounted thereon a twister hook composed of a body 80 from which projects an arm 81. There is a notch 82 at the junction of the arm and body and when shaft 76 is revolved the arm catches the wires and brings them into and holds them in notch 82. Shafts 71, 75, and 76 are mounted in a casing 83, mounted on plate 25, which 50 casing encloses the pinions and gear mounted on said shafts. Rigidly mounted upon the side of casing 83, adjacent to slide 51, is a plate 84, the top of which is bifurcated to form cutter bars 85 and 86. Shafts 75 and 76 project through this plate and the twister 55 hooks are mounted on shafts 75 and 76 adjacent to bars 85 and 86. These bars, as shown in Fig. 13, have the left hand edge at the top formed into a cutting edge. Pivotaly mounted upon plate 84 is a shear member 87, 70 the top of which is bifurcated with the right hand edges formed into a cutting edge forming blades 88 and 89, which with the tops of bars 85 and 86 form two shears into which the free ends of the wires to be spliced 75 are brought after being stripped of insulation. Member 87 has a shank or lug 90 on the lower end thereof which projects into a notch 91 in shear operating bar 92 which moves in guide 93 secured upon plate 25, as 80 best shown in Figs. 11 and 12. Bar 92 is connected by link 94 to lever 27, as best shown in Fig. 2. With a pair of wires in the slide and with the sleeves on one wire of each pair and with the insulation removed from the 85 skinning blades to the ends and with the ends passed through the shears, one pair through each shear, the operator moves lever 27 toward bar 26. The initial move causes the 90 twister hooks to engage the wires and each pair is forced into the notch of the twister hook of that pair. The shears are at the same time operated to cut off the surplus wire of the free ends and when lever 27 is brought the required distance toward bar 26 the re- 95 quired twist is formed in each pair of wires. During this movement of the inner end of lever 27, the outer end of lever 27 has moved to the right and beneath slide 51. The outer end of lever 27 has secured thereto a bearing 100 95^a in which is pivotally mounted a short link 95 which has a head 96. Link 95 as it moves to the right rides up and on a track 97, mounted upon plate 25, and just before the head reaches the limit of movement toward the right it lifts up and passes beyond a trigger 98 which is rockably mounted on the lower side of slide 51. The further movement causes head 96 to engage a lock bar 99 and depress the free end thereof and release 105 it from a catch 100 secured to the bottom of slide 51. When bar 99 is released from catch 100, slide 51 can move to the left. Bar 99 is secured to the slide guide frame 101, in which frame guide 51 is longitudinally movable. As soon as bar 99 is released from catch 100 the operator releases lever 27 and spring 29 moves the lever back to its inoperative or normal position. In its movement to the left, head 96 engages trigger 98 and carries both 110 the trigger and slide to the left until the head rides off track 97. A spring 102, one end of which is secured to slide 51 and the other to the slide guide frame, then returns the slide to its normal position. Just before slide 51 reaches its limit of movement to the left an ejecting lug 103, which projects from the side of the guide frame, engages trigger 55 and moves the trigger to carry the wire out of slot 58. To hold the wire from going back, 115 120 125 130

into slot 58, I provide a detent lever 104, which is pivotally mounted by pin 105 to guide bars 106 and 107, best shown in Figs. 3 and 9. A spring 108 holds lever 104 in its normal position, shown in Fig. 9. Slide 51 has a lug 129 which engages lever 104 as the wire is ejected from slot 58 and holds lever 104 to prevent the wire from entering slot 58 and the slide then moves to the right carrying the slit away from the wire. Lever 27 has attached thereto near the inner end, a shear lug 109, which engages a shear blade 110 pivotally mounted on a companion shear blade 111 when the inner end of lever 27 moves to the right. Blade 111 is mounted on plate 25. When lug 109 engages the bottom of blade 110, the top thereof shears past the top of blade 111 and cuts off the ends of the twisted wires that are in the twister hooks, leaving a twisted pigtail splice. Spring 110^a holds blade 110 normally in the position shown in Fig. 5. It will be understood that the wires pass between these blades as they are twisted as before explained. To eject the cut off twisted portion of the wires from the twister hooks, I prefer to make the hooks in two parts spaced apart on the shafts that carry the hooks. I mount on plate 25 a standard 112, in which is rockably mounted an ejector blade 113 which has a pointed upper end that projects between the two hooks and lies in contact with the shaft on which the hooks are mounted, as shown in Figs. 15 and 18. A spring 114 bears against blade 113 and permits it to yield to allow the wires to pass when the hooks are rotated to twist the wires, but will not yield when the hooks are rotated in the reverse direction and will thereby cause the cut off portion of the wires to be ejected from the hooks. As slide 51 is moved to the left, guides 60 turn the twisted uncut portion of the wires to the left. The further movement of the slide places the sleeve over such twisted portion and that portion of the splicing operation is finished. Other wires are then treated in like manner. While I have shown and described lever 27 as operated by hand, it is obvious that it could be operated by any suitable power, proper connections being made therefor.

A stop 130 limits the movement of the outer end of lever 27 to the right. The threads of bolt 48 are protected by a sleeve 131. Frame 101 is mounted upon plate 25 by standard 132. Where two pairs of wires are spliced at the same time each pair is passed between the blades of cutters. In Figs. 13 and 14 the double cutters are shown. In Fig. 14 the cutters for cutting off the wire after it is twisted which lies between the twister hooks and the slide is shown. This cutter comprises a standard 115 mounted on plate 25 whose top is bifurcated and the edges of the furcations are sharpened to form cutting blades 116 and 117. On standard 115 is pivotally mounted shear blade 118 by bolt 119. Blade 118 has a

bifurcated top and the edges are sharpened to coact with blades 116 and 117. The cutting edges are marked 120 and 121. A spring 122 holds blade 118 in its inoperative position as shown in Fig. 14. The lower end of blade 118 has projecting from the side thereof a lug 118^a that is engaged by lug 109 to operate blade 118. A guard 123 protects bar 68. It will be understood that each pair of wires has mounted thereon a sleeve which is positioned in the slide as before explained and after blade 118 operates the slide positions the twisted portions of the ends and slides the sleeve thereover the same as if a single pair was spliced. When fine wire is used the 80 twister hooks will twist the wires together so tightly that the twisted portion will break from the portions in the hooks at their outer edges and blades 110 and 111 are not necessary to be used.

Having described my invention, I claim:

1. In a machine for splicing cable wires, means to connect the machine to the cable comprising a base plate having parallel slots therein; a slotted connector bar extending across the slots in the base plate; bolts extending through said slots whereby said plate and bar are adjustably connected together; L shaped adjusting arms secured to the ends of said bar; and clamping members adjustably mounted on said arms.

2. In a machine for splicing cable wires, a base plate; means to adjustably connect said plate to the ends of a cable to be spliced; a plurality of twister hooks revolvably mounted 100 on said plate; means to operate said hooks, and means to hold said cable wires in said hooks.

3. In a machine for splicing cable wires, a base plate; means to connect said plate to the ends of a cable to be spliced; a plurality of 105 twister hooks revolvably mounted on said plate; means to hold and guide wires in said hooks; means to cut off the surplus portion of the twisted portion of the wires.

4. In a machine for splicing cable wires, a base plate; means to connect said plate to the ends of the wire of a cable to be spliced; a plurality of twister hooks revolvably mounted on said plate, wires to be spliced; a sleeve on one of said wires; means to hold and guide the wires; means to operate the hooks; means to cut off the excess of the twisted portions of said wires; and means to cause the sleeves to be passed upon the twisted portion of the wires.

5. In a machine for splicing cable wires, a base plate; an operating lever mounted on said plate; twister hooks mounted on said plate and a connection between said lever and hooks whereby when said lever is moved said hooks are operated, said connection having as a part thereof a yielding or compensating portion.

6. In a machine for splicing cable wires, a base plate; a slide guide mounted thereon; a

85

130

slide in said guide; means carried by said slide to hold a wire against coming out of said slide until the wires are twisted; and means to operate said holding means to eject a wire therefrom when a sleeve has been moved over the twisted portion of the wires.

7. In a machine for splicing cable wires, a base plate; a slide guide mounted thereon; a slide in said guide; means to lock said guide against movement during the time the wires are being twisted; and means to unlock said slide lock after the wires are twisted.

8. In a machine for splicing cable wires, means to twist the contiguous ends of two wires together; means to cut off the surplus portions of the twisted portions of the wires;

and means to eject said cut off portions from said twisting means.

9. In a machine for splicing cable wires, a base plate; means mounted on said plate to twist the loose ends of two wires together, said means comprising in part a shaft, twister hook mounted on said shaft, said hook comprising a body having a groove therein and a bifurcated arm projecting from said body angularly thereto to form a notch at the junction of said body and arm. 20 25

In witness that I claim the foregoing I have hereunto subscribed my name this 11th day of July, 1925.

JAMES W. CHANNELL.
